UNITED STATES PATENT OFFICE.

DAVID W. CONNELL, OF MOLINE, ILLINOIS, ASSIGNOR TO VELIE CARRIAGE COMPANY, OF MOLINE, ILLINOIS, A CORPORATION OF ILLINOIS.

VEHICLE-SHAFT.

No. 832,719.

Specification of Letters Patent.

Patented Oct. 9, 1906.

Application filed November 15, 1905. Serial No. 287,467.

To all whom it may concern:

Be it known that I, DAVID W. CONNELL, a citizen of the United States, residing at Moline, in the county of Rock Island and State of Illinois, have invented certain new and useful Improvements in Vehicle-Shafts; and I do hereby declare the following to be a full, clear, and exact description of the invention, such as will enable others skilled in the art to 10 which it appertains to make and use the same.

The object of this invention is to effectively strengthen vehicle shafts or thills where they bend down at the rear for attachment to the 15 vehicle-axle, and especially to strengthen and brace the bends against backing strain of the team.

Vehicle-shafts usually have their bends reinforced by metal straps bolted to the under 20 concave sides of the shaft, and the ends of these straps terminate in eyes or loops through which the coupling-bolts are passed for attaching the shafts to the axle. As so constructed the shafts are fully strong enough 25 to withstand the regular pulling strain, but are weak against any backing strain, often breaking when such strain is severe, as when a horse backs up grade or against some obstruction. Not only does this weakness 30 exist in the curved portion of the wooden shaft-bar, which is not materially strengthened by its under strap against backward strains, but, moreover, the backing of the horse tends to bend the lower end of the strap where it couples to the axle and to pull it away from the 35 under side of the shaft. As the strap is weakest where the bolt-hole comes, it frequently breaks just above the eye. In some instances vehicle-makers have attempted to 40 strengthen the shaft by straight brace-rods. These merely strengthen the shafts against forward pull, which is not needed, but do not materially strengthen the same against backing strain. The present invention overcomes 45 all such defects and provides a shaft perfectly braced and strengthened against both pulling and backing strains by simple and inexpensive means substantially as illustrated in the accompanying drawings, which 50 form a part of this specification.

In said drawings, Figure 1 is a side view of a fragment of a vehicle-shaft—namely, the rear bend or curved portion thereof—having my invention embodied therein. Fig. 2 is a

longitudinal vertical section of the same. 55 Fig. 3 is a detail view of the curved brace-rod, which is the chief element of my invention. Fig. 4 is a top plan view of the fragment of the shaft shown in Figs. 1 and 2, showing also a part of the cross-bar which 60 connects the rear portions of the two shafts. Fig. 5 is a vertical cross-section on line X X of Fig. 2.

A particular explanation of the illustrated device is as follows: The shaft A, in addition 65 to its regular under reinforcement of the strap-iron B, has its rear bend or curved portion strengthened by a brace-rod C, the same being a tension-rod curved to conform to the upper or convex side of the bend against 70 which it lies and tightly connecting the shaft A in front of the bend with the rear lower end of the strap-iron B. Said brace-rod C is preferably seated in a groove therefor in the upper side of the shaft-bar desirably to the depth of about half its own width or diameter. Its front end has an eye 75 c, engaging the rear bolt d of the T clip or iron D, which connects the shaft A to its cross-bar E. The rear end of said brace-rod, 80 which is threaded at c', enters an aperture therefor in the rear lower end of the strap B and has a nut c² screwed thereon, the nut being adjusted to tighten the rod to make the brace effective. 85

This device accomplishes a twofold result. In the first place it strengthens the bend of the shaft-bar perfectly against any backward strain due to backing of the horse. Furthermore, it ties the under strap B to the wooden 90 shaft-bar just in front of the eye b and in this way makes it impossible for the strap to be broken or pulled from the shaft-bar by the backing of the animal. By means of the nut or by any equivalent means at the lower end 95 of the brace-rod perfect adjustment of the brace can be had and proper tension given to the rod to meet the requirements of usage. As the brace-rod is seated in the top of the shaft-bar, when it is painted it presents a neat 100 appearance and adds to the attractiveness of that part of the shaft. It resembles a bead running from the T-iron backward and downward to the end of the shaft. It does away with the awkward appearance of the straight 105 brace-rod, such as heretofore used in some cases, and supplies the deficiency of such rods by giving strength to the shaft. The heads

of the bolts *a*, that hold the strap *B* to the shaft, are seated in the wood of the shaft underneath the brace-rod, so that these bolt-heads are entirely concealed.

5 In the following claims the word "shaft" is to be construed so as to include any equivalent member, such as the rear portion of a vehicle tongue or pole.

Having thus fully described my invention, 10 what I claim as new, and desire to secure by Letters Patent of the United States, is—

1. A vehicle-shaft having its bend provided with a tension-rod as a unitary part of said shaft, the opposite ends of said rod being fixedly secured directly to or on the shaft itself, and means for tensioning said rod, the arrangement being such that the tension of the rod acts on the bend in a manner tending to straighten the same.

2. A shaft having its bend reinforced by an under strap, and a curved brace-rod seated against the upper side of the bend and connected to the shaft at the front of the bend and connected to the rear lower end of the under strap, and means for tensioning said rod.

25 3. A shaft having a strap attached to the under side of its bend, said strap terminating in an eye for a coupling-bolt, and a brace-rod attached to the upper side of said bend, the rear end thereof passing through the strap in front of its eye, and a nut screwed on said end of said rod for tightening the same.

4. A shaft having its bend reinforced by a strap on the under side thereof and a tensioned brace-rod on the upper side thereof, the forward end of the brace-rod having an eye which engages one of the bolts that bind the strap to the shaft, and the rear end of the brace-rod being adjustably connected to the strap in such manner as to allow adjustment of the tension of said rod.

40 5. A shaft having its bend reinforced by

an under strap, and having a longitudinal groove in the upper side of its bend, and a brace-rod seated in said groove having its 45 forward end attached to the shaft and its rear end attached to the strap.

6. A shaft having its bend reinforced by an under strap attached thereto and terminating in a thill-coupling, and a brace-rod seated 50 against the upper side of the bend having its forward end bolted to the shaft and its rear end inserted through the strap immediately in front of the thill-coupling, and a nut screwed on said rear end for tightening the 55 brace-rod.

7. A shaft having a brace-rod applied to the upper or convex side of its bend, the front and rear ends of said brace-rod being attached directly to the shaft itself, and means 60 for adjusting the tension of said brace-rod, said adjusting means being independent of the means for coupling the shaft to the vehicle.

8. A shaft having its bend reinforced by an 65 under strap, and a brace-rod applied to the upper side of the bend having its front end attached to the shaft and its rear end connected to said under strap at the rear lower end of the shaft, and means for adjusting the tension 70 of said brace-rod.

9. A shaft having a strap attached to its bend, said strap terminating in a thill-coupling at the rear lower end of the shaft, and a tie-rod connecting said thill-coupling with the 75 shaft and opposing the pull on the thill-coupling due to a backing strain on the shaft.

In testimony whereof I affix my signature in presence of two witnesses.

DAVID W. CONNELL.
